UNITED STATES PATENT OFFICE.

EDGAR N. BLOCK, OF BUFFALO, NEW YORK, ASSIGNOR TO EMPIRE STATE RING COMPANY, OF BUFFALO, NEW YORK, A COPARTNERSHIP.

FINGER-RING.

1,186,271.

Specification of Letters Patent. Patented June 6, 1916.

Application filed December 20, 1913. Serial No. 807,806.

To all whom it may concern:

Be it known that I, EDGAR N. BLOCK, a citizen of the United States, residing at Buffalo, in the county of Erie and State of New York, have invented new and useful Improvements in Finger-Rings, of which the following is a specification.

This invention relates to finger rings and has the object to provide a ring of this character which can be produced expeditiously and at comparatively low cost and which will permit of readily and conveniently interchanging the ornament, stone or jewel without detracting from the artistic appearance of the ring.

In the accompanying drawings: Figure 1 is a front elevation of a finger ring embodying one form of my invention. Fig. 2 is a side elevation thereof partly in section. Fig. 3 is a top plan view of the same. Fig. 4 is a transverse section of the ring taken in line 4—4, Fig. 2. Fig. 5 is a longitudinal section taken in line 5—5, Fig. 1. Fig. 6 is a front elevation of a ring showing a modification of my invention. Fig. 7 is a longitudinal section taken in line 7—7, Fig. 6.

Similar characters of reference indicate corresponding parts throughout the several views.

Referring to the construction shown in Figs. 1—5, 1 represents an intermediate band which is of substantially crescent-shaped form and provided at its opposite upper ends with claws 2. On opposite sides of this intermediate band are arranged two bands 3—3 of substantially circular form and provided on the inner opposing sides of their upper parts with recesses or seats 4, 4. These bands may be constructed of any suitable metal or material by any desired means, for instance, by the usual and well known method of stamping or casting. These bands are arranged axially side by side and have their lower parts united preferably by soldering so that they are permanently secured together while their upper ends are separated from each other, so that the upper ends of the circular bands diverge relatively to each other and to the intermediate band, as shown in Figs. 2, 3 and 5. The plurality of bands thus united form the body setting or mounting of the ring and upon the upper parts of the same an ornament, jewel or stone 5 of any suitable character may be mounted by seating or engaging the oppo-

site ends of this ornament in the recesses or seats in the upper parts of the circular bands and engaging the claws of the intermediate crescent-shaped band with the opposite side edges of the ornament, as shown in Figs. 2—5. The metal of which the bands are made is sufficiently flexible or malleable to permit of separating the upper parts of the bands and engaging the same with the ornament. If desired, the mere closing of the upper parts of the several bands against the ornament may suffice to hold the ornament in place. It is preferable, however, to use additional means for securely holding the upper parts of the bands against displacement and thus confine the ornament more securely between the same. For this purpose it is preferable to employ two ties or clamping members 6 of any suitable construction such as the screws which are shown in the drawings and which extend lengthwise through corresponding openings in the upper parts of the bands on opposite sides of the ornament and parallel with the axis of the ring. These ties may either be constructed in the form of screws each of which engages its head with the top of one of the circular bands and its opposite threaded end with a thread in the opening in the upper part of the other circular band, as shown in Figs. 1, 2, 3 and 5, or these tie members may be constructed in the form of bolts or rivets. When constructing the body of the ring of three bands, as shown in Figs. 2, 3 and 5, the same is comparatively heavy and more suited for use as a gentleman's ring.

In adapting my invention for use in lighter rings, such for instance, as those designed more particularly for ladies' use, the intermediate crescent-shaped band may be omitted and in this case the lower parts of two circular bands 7, 7, are secured directly to each other while their upper parts are separated and provided on their opposing inner sides with recesses or seats 8, 8, in which the opposite ends of the ornament, stone or jewel 9 is seated, as shown in Figs. 6 and 7. In this last mentioned construction the separated upper parts of the circular bands are connected with each other for confining the ornament reliably between the same by means of two ties 10, 10 which are constructed in the form of rivets as shown, or in the form of bolts, and arranged lengthwise on opposite sides of the ornament in

corresponding openings formed in the adjacent upper parts of the circular bands. It will be noted that in all of the foregoing constructions a circular body is produced the 5 lower part of which is practically solid in its finished state while the upper part is divided so as to form two circumferential bridges separated by an intervening space and provided on their opposing sides with 10 seats which are held in engagement with opposite sides of the jewel or ornament by clamping means adjustably connecting said bridges.

My improved construction of finger rings 15 renders it possible for a jeweler to readily interchange one ornament, jewel or stone for another in the setting or mounting in order to suit the particular needs of the customer, thereby enabling a jeweler to meet the requirements of the trade by carrying a comparatively small number of ring bodies or 20 settings which are adapted to receive ornaments of various designs, whereby the amount of jewelry which must be kept on 25 hand and the amount invested in the same may be materially reduced.

I claim as my invention:

1. A finger ring comprising a plurality of circular non-expansible bands arranged 30 axially side by side and having their lower parts connected while their upper parts are separated and provided on their opposing sides with seats adapted to receive opposite edges of an ornament and a clamping device 35 connecting the upper parts of said bands.

2. A finger ring comprising a plurality of circular bands which are arranged axially side by side and have their lower parts connected so that said bands are permanently 40 held in axial alinement while their upper parts are separated, an ornament arranged between the disconnected parts of said bands, and ties connecting the separated parts of said bands.

45 3. A finger ring comprising a plurality of circular bands which are arranged side by side and have their lower parts connected so that said bands are permanently held in

axial alinement while their upper parts are separated, an ornament arranged between 50 the disconnected parts of said bands, and ties connecting the separated parts of said bands and arranged lengthwise on opposite sides of said ornament.

4. A finger ring comprising a plurality of 55 circular bands which are arranged side by side and have their lower parts connected so that said bands are permanently held in axial alinement while their upper parts are separated and are provided on their opposing 60 inner sides with seats, an ornament having opposite edges thereof seated in said seats, and longitudinal ties connecting the separated parts of said bands.

5. A finger ring comprising an intermediate 65 crescent-shaped band which is provided at its upper end with claws and two circular bands arranged on opposite sides of the intermediate band and having their upper ends provided with seats, the lower 70 parts of said bands being united and the upper parts of said circular bands being spread apart, and an ornament seated with its opposite ends in the seats of the circular bands and engaged on its opposite sides by said 75 claws of the intermediate band.

6. A finger ring comprising an intermediate crescent-shaped band which is provided at its upper end with claws and two circular bands arranged on opposite sides of the 80 intermediate band and having their upper ends provided with seats, the lower parts of said band being united while the upper parts of the circular bands are spread apart, an ornament seated with its opposite ends in 85 the seats of the circular bands and engaged on its opposite sides by said claws of the intermediate band, and longitudinal ties engaging with said circular and intermediate bands on opposite sides of said ornament. 90

Witness my hand this 18th day of December, 1913.

EDGAR N. BLOCK.
